UNITED STATES PATENT OFFICE.

ABRAHAM LINCOLN STROUSE AND SAMUEL WEINSCHENK, OF NEW YORK, N. Y.;
SAID STROUSE ASSIGNOR OF HIS ENTIRE RIGHT TO NATHAN SHAW, OF NEW
YORK, N. Y.

ARTICLE OF FURNITURE.

Application filed November 28, 1924. Serial No. 752,698.

To all whom it may concern:

Be it known that we, ABRAHAM LINCOLN STROUSE and SAMUEL WEINSCHENK, both citizens of the United States, and residents, respectively, of the city of New York, borough of Manhattan, in the county and State of New York, and of the city of New York, Richmond Hill, borough of Queens, in the county of Queens and State of New York, have invented a new and Improved Article of Furniture, of which the following is a full, clear, and exact description.

The present invention relates to new and useful improvements in furniture, and it pertains more particularly to articles of furniture so constructed as to be readily knocked down or disassembled.

It is one of the primary objects of the invention to provide an article of knock-down furniture which may be transported in the knockdown condition and readily assembled upon arrival at its destination.

It is a further object of the invention so to construct the article of furniture that when in its set-up position it will be rigid for the support of various articles to be carried thereby.

While in the present instance the article of furniture is shown as an umbrella stand, it is obvious that other articles of furniture may be constructed in the same manner without departing from the spirit of the invention, and the invention is not limited to umbrella stands.

With the above and other objects in view, reference is had to the accompanying drawings, in which—

Figure 1 is a perspective view of an umbrella stand constructed in accordance with the present invention, the stand being shown in its set-up position;

Fig. 2 is a perspective view of the main elements of the stand, in detached relation;

Fig. 3 is a top plan view of the stand.

Referring more particularly to the drawings, the invention comprises side members and end members which are detachably connected together and are of such construction that they will readily nest when in their knockdown position, and when placed together in set-up position will provide a rigid structure.

Each of the side members, of which there are two, comprises two longitudinally-ex-

tending members 10, which are connected together in spaced relation and maintained in spaced relation by a lower transversely-extending member 11 and an upward transversely-extending member 12. The upper end member is designated by the reference numeral 13, and such upper end member is provided with a plurality of openings 14, the purpose of which will be hereinafter described. Carried by the upper end member 13, on each of two of its oppositely-disposed sides, there are blocks 15. These blocks are of a length substantially equal to the distance between the members 10 heretofore mentioned and are adapted to occupy a position therebetween as shown in Fig. 1.

The reference numeral 16 designates the lower end member and such lower end member in the present instance is provided with a recessed portion 17. This lower end member is provided on each of two of its oppositely disposed sides with blocks 18, and these blocks 18 are of a length equal to the space between the side members 10, and are adapted to occupy a position therebetween when the several sections are placed in their set-up form. Pivotedly secured to each end of one of the upper end members 12, as at 19, there is a locking member 20, and each of these locking members is notched, as at 21, to receive a pin or the like, 22, secured, as at 23, to the opposite ends of the member 12 to which the locking members 20 are not pivoted.

The device is assembled in the following manner:

With the parts in the position shown in Fig. 2, the member 13 is positioned on the transversely-extending members 12 with the blocks 15 occupying a position between the members 10. The lower end member 16 is positioned upon the transversely-extending members 11 with the blocks 18 occupying a position between the members 10, as shown in Fig. 1. After this has been done, each of the locking members is engaged with its respective pin 22 in order to provide a more rigid assembly.

With the device in the set-up position shown in Fig. 1, it is obvious that umbrellas inserted in the openings 14, with their lower ends in the recess 17 of the lower end member 16, will be retained in an upright position.

What is claimed is:

1. A knockdown umbrella stand, comprising upper and lower end members, side members, and means for separably holding all of said members in set-up condition in which the end members are spaced from each other and in which the said side members are spaced from each other, said means comprising portions on the end members which fit between portions on the side members and locking members pivotally connected to one of said side members and releasably engageable with the other side member.
- 15 2. An article of knockdown furniture comprising upper and lower end members, the upper end member having a plurality of receiving openings therein and depending blocks, the lower end member being dished and having depending blocks, side members each comprising longitudinals

and upper and lower cross pieces respectively connecting the longitudinals near their opposite ends with said longitudinals spaced from each other, said lower end member being supported by the lower cross pieces with the blocks thereof disposed respectively between the adjacent end portions of the longitudinals in contact therewith and in contact with the lower cross pieces, said upper end member being supported by the upper cross pieces with the blocks thereof disposed respectively between the adjacent end portions of the longitudinals in contact therewith and in contact with the upper cross pieces, and locking members pivotally connected to one of said side members and releasably engageable with the other side member.

ABRAHAM L. STROUSE.
SAMUEL WEINSCHENK.
